ROADSIDE SIGN

Baron G. Roberts, Atlanta, Ga., assignor to Gold Platter, Inc., Macon, Ga., a corporation of Georgia

Filed Oct. 10, 1969, Ser. No. 19,500

Term of patent 14 years

Int. Cl. D20—03

U.S. Cl. D96—12

FIG. 4

FIG. 2

FIG. 1

FIG. 3

FIG. 1 is a side elevational view of a roadside sign embodying my new design;

FIG. 2 is a front elevational view thereof;

FIG. 3 is a rear elevational view thereof; and

FIG. 4 is a top plan view thereof.

I claim:

The ornamental design for a roadside sign, as shown and described.
